UNITED STATES PATENT OFFICE.

WILLIAM M. SHEEHAN, OF ST. LOUIS, MISSOURI, ASSIGNOR TO COMMONWEALTH STEEL COMPANY, OF ST. LOUIS, MISSOURI, A CORPORATION OF NEW JERSEY.

LOCOMOTIVE UNDERFRAME.

Application filed April 9, 1926. Serial No. 100,840.

My invention relates to railway rolling stock and consists in an improved underframe, particularly adapted for use on locomotives having electric motors mounted on the trucks thereof.

One of the objects of my invention is to more effectively utilize the underframe to form conduits for the flow of air from blowers carried by the locomotive to the motors mounted on the locomotive trucks.

Another object of my invention is to adapt the underframe to form ballast compartments.

Both of the above objects are obtained by utilizing the space between the upper and lower faces of the underframe sill members, thereby avoiding the demand for space above the underframe for the purposes mentioned and also providing a lower center of gravity for the locomotive.

Another object of my invention is to construct an underframe for the purpose referred to of a one-piece casting and to adapt the casting so as to facilitate the flow of air therethrough and the carrying of ballast thereon.

Another object of my invention is to provide steps, lifting hook recesses, push pole pocket brackets, improved truck safety chain lugs, and suitable brackets and pads for mounting blowers, compressors, and other apparatus on the underframe, all these parts being formed integrally with the underframe.

In the accompanying drawings illustrating a selected embodiment of my invention,

Figure 1 is a top view of one-half of an underframe embodying my invention.

Figure 2 is a side elevation of the same.

Figure 3 is a longitudinal vertical section taken on line 3—3 of Figure 1.

Figure 4 is a transverse vertical section taken on line 4—4 of Figure 1.

Figure 5 is a transverse vertical section taken on line 5—5 of Figure 1.

Figure 6 is a detail horizontal section taken on line 6—6 of Figure 2.

Figure 7 is a detail vertical section taken on line 7—7 of Figure 1.

Figure 8 is a section on line 8—8 of Figure 4.

The underframe includes center sills 1 which are flanged top and bottom and the inner flanges of one sill are joined as at 7

to the inner flanges of the other sill throughout most of their length, forming a substantially box-shaped girder between the bolsters. Side sills 2 and intermediate sills 3 also extend lengthwise of the underframe 60 and the transverse members comprise the bolsters formed of spaced elements 4 and 5, suitable transoms 6, and end sills 8.

The above members are provided with projections 31 having suitable pads for 65 mounting the motor compressor, and similar projections 32 are provided for mounting the motor blower.

The webs of the center sills and the ties and portions of the top and bottom flanges 70 of the same form sides and portions of the horizontal walls of an air passage or conduit extending between the bolsters, which conduit is completed by the addition of plates 9 and 10 which are secured, respectively, to the top and bottom of flanges of the center sills. The transverse edges of each portion 7 are beveled as indicated at 11 to reduce the resistance offered by the member to the passage of air therethrough. 80

The inner bolster element 5 and the adjacent members 7 are reinforced by a longitudinal vertical rib 13 which is located centrally of the air conduit and has its edge 85 opposed to the direction of flow of air so as to offer the least resistance to the passage of air past the same.

Air is admitted to the conduit at the rectangular opening 12 adjacent the righthand bolster illustrated, and air is discharged 90 from the conduit to the truck structure through the center plate structure at each bolster as best indicated in Figure 4, or through opening 37 as best indicated in Figure 3. Either discharge opening may be 95 used according to the truck structure desired, the opening not used being closed by a suitable cover plate as indicated at P by broken lines.

The air may be supplied to the conduit 100 through opening 12 in any well-known manner and is led from the discharge opening to the motors by any additional conduit particular forms thereof being illustrated in my copending applications Serial Numbers 105 114,742 and 114,743, filed June 9, 1926.

The center plate 14 has an annular form providing a central opening through which air can pass and is adapted to fit into a similar annular truck center plate 33, the latter 110

being indicated in Figure 4 and not claimed as part of my present invention.

The side and intermediate sills of my underframe are substantially Z-shaped in cross section with their upper flanges facing away from each other and their inner flanges facing toward each other. With this arrangement a series of plates 16 may be laid upon the lower flanges and plates 16 and the sill webs form a compartment into which rails or slabs of cast iron or other ballasting material may be placed without taking any room above the upper surface of the frame. If desired, these ballast compartments may be covered with plates 17.

By offsetting the web of the side sill inwardly as indicated at 18 I provide for a step. This step is completed by extending the web of the side sill downwardly a short distance below its inwardly extending lower flange and projecting an outwardly extending flange 19 on this downward extension. (See Fig. 7). Flange 19 may be roughened to provide a secure foot-hold and its outer edge may have a lip 20 to guard the foot of the user against being inserted beneath the step. The outwardly extending upper flange is cut away at the offset portion of the sill as indicated at 21 to provide sufficient clearance in using the step.

The web of each side sill preferably has diverging lower portions 22 and 23 at the bolster which form recesses adapted to receive a lifting cable or hook C or similar device. I reinforce the outer portion 23 of the web by suitable ribs 24. The edges of the web which are engaged by the cable are rounded to prevent injury to the latter.

At 25 I show the side sill depressed to provide a space for the integral safety chain lug 26, the depressing of the side sill web enabling me to provide the lug without projecting the same beyond the outer edge of the side sill upper flange. This depression is made of sufficient length to permit easy application and removal of a safety chain pin or bolt, and the lug is located nearer to one end of the recess than to the other, thereby insuring that a workman can only insert the bolt from one direction which may be desirable in order to produce proper application of the chain.

At the end of the side sill and end sill the corner of the underframe is formed by a downward extension 27 which provides space for a push pole pocket 28 facing diagonally outward from the end of the frame. At the center of the end sill the same has an integral downward extension 29 connected to a similar downward extension 30 on the ends of the center sills, the last described structure bracing this portion of the end sill to absorb the buffing stresses.

With my structure as hereinbefore described, a number of parts which have hith-

erto been eliminated or provided by the addition of separate elements to the underframe are formed integrally with the remainder of the underframe and the structure as a whole may possess more strength for a given weight of material than would be possible with a built-up structure. The labor of assembling the different parts is eliminated and the necessity of tightening or replacing securing elements, such as bolts and rivets, is also eliminated. The parts formed on the side sill are added thereto without extending beyond clearance lines and the parts formed in the body of the frame, such as the air conduit and ballast compartment, are enclosed and protected by the main members of the underframe.

Many of the details of my structure may be modified without departing from the spirit of my invention, and I contemplate the exclusive use of such changes and arrangement in structure as fall within the scope of the appended claims.

I claim:

1. In an electric locomotive underframe, spaced flanged sills forming an air conduit between their webs and flanges and extending longitudinally of the frame.

2. In an underframe for electric locomotives, transversely spaced longitudinal sills, bolsters, and a passage between said sills from bolster to bolster for air to cool the locomotive motors.

3. In an underframe for electric locomotives, transversely spaced longitudinal sills, said sills forming the sides of a conduit for a motor cooling air current.

4. In an underframe for electric locomotives, an integral longitudinal member of box section, the interior of which forms a conduit for distributing an air current.

5. In an underframe for electric locomotives, longitudinal sills, vertically spaced horizontal flanges on said sills for attaching top and bottom walls of an air conduit leading to the locomotive motors, and transverse portions connecting said flanges and having edges beveled to reduce resistance to the passage of air through said conduit.

6. In a cast underframe for electric locomotives, spaced sills, and sill connecting ties formed integrally therewith, and having their inner surfaces beveled outwardly to reduce resistance to the passage of air past the same.

7. In an electric locomotive underframe, spaced sills, and a bolster formed of spaced elements, there being an air conduit extending longitudinally of the frame between said sills and transversely of the sills between said bolster elements.

8. In an electric locomotive underframe, spaced center sills, bolsters, a passage between said center sills from bolster to bolster for air to cool the locomotive motors, center

- plates on said bolsters, an inlet to said passage between said bolsters, and outlets from said passage through said center plates.
9. In an electric locomotive underframe, spaced sills extending longitudinally of the frame and having imperforate vertical webs, bolsters, a center plate on each of said bolsters, each of said bolsters including vertical webs surrounding three sides of its center plate and forming with said sills a continuous air conduit leading from a point intermediate said bolsters through said center plates to the locomotive truck.
10. In combination, a locomotive underframe including a bolster, a center plate thereon, there being an air conduit from the underframe through the side of said bolster and through said center plate to the locomotive truck.
11. In an underframe, a side sill, and an intermediate sill having lower flanges extending toward each other, said sills forming side and bottom wall portions of a ballast compartment.
12. In an underframe, a side sill, Z-shaped in cross section, with its lower flange extending inwardly and its upper flange extending outwardly, and an intermediate sill similarly spaced but with its respective flanges extending oppositely to said side sill flanges, a plate resting on the lower flanges of said sills and with the webs of said sills forming a ballast compartment.
13. A cast underframe including Z-shaped side and intermediate sills with their lower flanges facing each other, said sills being adapted to support and retain a plate between them to provide a ballast receptacle near the side of the underframe.
14. In a one-piece cast railway underframe, spaced center sills, and spaced side and intermediate sills on each side of said center sills, said center sills cooperating to form an air conduit, and said side and intermediate sills cooperating to form ballast compartments, said conduit and compartments being located between the top and bottom surfaces of said underframe.
15. In an electric locomotive underframe, a bolster, the middle portion of which forms part of an air conduit, the inner and lower walls of said bolster having openings to provide for the passage of air from the center of the underframe through said bolster to a truck.
16. In an electric locomotive underframe, spaced center sills, bolsters each comprising spaced vertical walls intersecting said center sills, said sills and bolster walls forming portions of air conduits leading from the intermediate part of the locomotive underframe to the locomotive truck.
17. In a locomotive underframe, a side sill having a lateral depression formed therein, and a step at the bottom of said depression.
18. In a locomotive underframe, a Z-shaped side sill having its web offset rearwardly for a portion of its length and there extended downwardly and having an outwardly extending lower flange thereon to provide a step.
19. In a cast underframe, a side sill Z-shape in cross section with its upper flange facing outwardly, said sill having a portion offset inwardly and downwardly with an outwardly extending lower flange, said offset and flange forming a step enclosed at its ends and located below the level of the remainder of the sill.
20. In a locomotive underframe, a side sill including a vertical web, a portion of which has integral downwardly diverging flanges forming a recess for engaging a lifting hook.
21. In an underframe casting, a side sill, a portion of which is bulged outwardly and is provided with integral reinforcing ribs on its outer side and is provided with a corresponding inwardly extending integral element adjacent said bulge, said portion and elements forming a downwardly facing pocket for lifting hooks.
22. In an underframe, a side sill having a vertical web depressed inwardly throughout a portion of its length, and a transversely extending lug on the outer face of said depressed portions for attaching safety chains or the like.
23. In an electric locomotive underframe, spaced sills and spaced upper and lower walls forming an air conduit, and a vertical reinforcing member between said walls having its edge rounded to reduce resistance to air passed through said conduit.
24. In an electric locomotive underframe, a bolster having upper and lower walls, an air conduit leading to the interior of said bolster, a vertical rib located in said conduit and connecting and reinforcing said walls, and having its edge rounded to reduce resistance to the passage of air by the same.
25. In an underframe, a side sill having a restricted portion depressed inwardly, a safety chain lug extending transversely of said portion and located nearer to one end of said portion than to the other end thereof.
26. In a locomotive underframe, a side sill having an integral portion provided with a downwardly facing recess adapted to receive a lifting element, the outer edges of said recess being rounded to avoid injury to such an element.
27. In a locomotive underframe, a side sill, an outwardly and downwardly projecting flange of restricted length integral with said sill beneath and around the ends of which flange a lifting cable or like element may be passed.
28. In an underframe for electric locomotives, a longitudinal draft member of

box cross section, the interior of which forms a conduit for distributing an air current.

29. In an underframe for electric locomotives, transversely spaced longitudinal ⁶ sills, bolsters, a longitudinal member of box cross section between said sills, the interior of which forms a conduit from bolster to bolster for passing an air current to cool the locomotive motors.

19 30. In an underframe for electric locomotives, transversely spaced longitudinal sills, a longitudinal member of box cross section between said sills, the interior of which forms a conduit for distributing an ¹⁵ air current, transversely disposed elements connecting said sills and member, said transverse elements having flanges connected to the top and bottom walls of said member.

20 31. In an underframe for electric locomotives, a longitudinal draft member of box cross section, and a bolster of box cross section, the interior of said member and of said bolster forming a conduit for distributing an air current.

25 32. In an underframe for electric locomotives, spaced bolsters, a longitudinal draft member of box cross section, the interior of which between said bolsters forms a conduit for distributing an air current, center plates on said bolsters, an inlet to said conduit between said bolsters, and outlets from said conduit through said center plates.

35 33. In an underframe for electric locomotives, bolsters, a longitudinal member of box cross section, a center plate on each of said bolsters, each of said bolsters including vertical webs surrounding three sides of its center plate and forming with said member a continuous air conduit leading from a point intermediate said bolsters through said center plates to the locomotive truck.

40 34. In an underframe for electric locomotives, a longitudinal member of box cross

section, a bolster including spaced vertical walls intermediate said member, said member and bolster walls forming portions of an air conduit leading from the intermediate part of the locomotive underframe to the locomotive truck. ⁴⁵

35. In an electric locomotive underframe, ⁵⁰ a longitudinal member of box cross section, the interior of which forms an air conduit and a vertical reinforcing element extending longitudinally of the underframe and spaced between the vertical walls of said longitudinal member, the edge of said element being rounded to reduce resistance to air passed through said conduit.

36. In a one-piece cast underframe for electric locomotives, a longitudinal draft ⁶⁰ member of box cross section, the interior of which forms a conduit for distributing an air current.

37. In a locomotive underframe, a side sill presenting a flush exterior vertical face ⁶⁵ throughout the major portion of its length, and a step element of restricted length extending downwardly and outwardly from said sill and formed integrally therewith.

38. In a locomotive underframe, a side ⁷⁰ sill presenting a flush exterior vertical face throughout the major portion of its length but having a short offset section, and a step element adjacent said section extending downwardly and outwardly from said sill ⁷⁵ and formed integrally therewith and having its end and inner edge enclosed.

39. In a locomotive underframe, a Z-shaped side sill having a portion of its web extending downwardly beyond the lower ⁸⁰ flange of the Z and provided with an outwardly extending flange thereon to provide a step.

In testimony whereof I hereunto affix my signature this 16th day of February, 1926.

WILLIAM M. SHEEHAN.
